CLAIM

The ornamental design for a tire repair tool, as shown and described.

DESCRIPTION

FIG. 1 is a side view of the tire repair tool showing our new design, the opposite side being a mirror image; FIG. 2 is a front view of the handle portion thereof; FIG. 3 is back view of the shank portion thereof; FIG. 4 is a front view of the shank portion thereof; and FIG. 5 is a perspective view thereof.

The shank portion of the tool is omitted in FIGS. 3 and 4 and the handle portion is omitted in FIG. 2 for illustrative purposes only.

FIG. 1

FIG. 5
